CONTAINER FOR A PHYLACTERY OR
SIMILAR ARTICLE

Emanuel Weiszberg, New York, N. Y.

Application December 21, 1950, Serial No. 13,522

Term of patent 14 years

(Cl. D58—12)

To all whom it may concern:

Be it known that I, Emanuel Weiszberg, a citizen of the United States, residing at New York, in the county of New York and State of New York, have invented a new, original, and ornamental Design for Container for a Phylactery or Similar Article, of which the following is a specification, reference being had to the accompanying drawing, forming part thereof.

In the drawing

Fig. 1 is a top rear perspective view of a container for a phylactery or similar article showing my new design;

Fig. 2 is a front perspective view thereof with the cover open; and

Fig. 3 is a bottom plan view thereof.

I claim:

The ornamental design for a container for a phylactery or similar article, as shown.

EMANUEL WEISZBERG,
